UNITED STATES PATENT OFFICE

SALVATORE MAZZELLA, OF PRINCETON, NEW JERSEY

REMOVABLE BRUSH HEAD

Application filed May 20, 1932. Serial No. 612,559.

This invention relates to certain new and useful improvements in removable brush heads.

The primary object of the invention is to provide a brush backing with a removable head carrying bristles or the like so that the latter may be removed from the backing for purposes of cleaning or replacement whenever desired.

10 A further object of the invention is to provide a removable brush head of the foregoing character with a thumb notch or depression in the brush head to facilitate removal thereof from the backing and with a novel form of 15 fastening device for retaining the brush head assembled on the backing.

With the above and other objects in view that will become apparent as the nature of the invention is better understood, the same 20 consists in the novel form, combination and arrangement of parts hereinafter more fully described, shown in the accompanying drawing and claimed.

In the drawing:—

25 Figure 1 is a bottom plan view of a brush constructed in accordance with the present invention, showing the head in assembled relation to the brush backing;

Figure 2 is a side elevational view;

30 Figure 3 is a bottom plan view with the brush head illustrated as partially removed from the backing;

Figure 4 is a cross-sectional view taken on line 4—4 of Figure 1, showing the interlocking sliding connection between the brush head and backing; and

Figure 5 is a detail sectional view taken on line 5—5 of Figure 1, showing the connecting device between the brush head and backing.

40 While the brush disclosed herein is in the form of a hair brush, it is to be understood that the inventive features of the device may be embodied in a brush of any character, 45 wherein a brush backing has a head removably engaged therewith. Referring more in detail to the accompanying drawing, the reference character 10 designates a brush backing having a reduced neck portion 11 and a gripping handle 12. The backing 10 has one

face thereof together with the reduced neck portion 11 cut away to provide longitudinally extending side edge flanges 13 with opposed faces of the flanges uppercut as at 14 to provide dove-tail retaining flanges for the 55 brush head. The cut away face of the backing 10 and neck 11 also provides an abutment shoulder 15 at the end of the handle 12 adjacent the neck 11. As shown more clearly in Figure 5, the abutment shoulder 15 is provided with an end opening socket 16 for purposes presently to appear.

The brush head 17 carrying bristles 18 upon one face thereof has the opposite face longitudinally grooved at its side edges to provide dove tail grooves 19 to receive the dove tail side flanges 13 as will be understood from an inspection of Figure 3. The inner end of the brush head 17 has a reduced neck portion 20 terminating in an abutment shoulder 21, 70 the reduced neck portion 20 mating with the reduced neck 11 of the backing while the shoulder 21 abuts the shoulder 15 of the handle 12.

An eye bolt 22 projects outwardly of the 75 end of the abutment shoulder 21 of the brush head 17 and moves into the socket 16 provided in the end of the shoulder 15 upon the handle 12. As shown in Figures 3 and 5, a threaded washer 23 is countersunk in the face of the 80 handle 12 above the socket 16 and through which washer the screw 24 is threaded by means of the head 25, the screw 24 passing through the eye-bolt 22 for securely anchoring the brush head 17 in the backing 10.

To remove the brush head from the backing for purposes of cleaning or replacement, the screw 24 is disengaged from the eye-bolt 22 and the thumb or forefinger of a person is placed in the notch or depression 26 in the 90 exposed side of the brush head in the reduced neck portion 20 thereof to facilitate sliding movement of the brush head relative to the brush backing and to aid in removal of the brush head.

95 From the above detailed description of the invention, it is believed that the construction and operation thereof will at once be apparent and while there is herein shown and described the preferred embodiment of the in- 100

vention, it is nevertheless to be understood that minor changes may be made therein without departing from the spirit and scope of the invention as claimed.

5 I claim:—

1. A brush comprising a back, a handle on the backing, the backing being cut-away on one face to provide side dove tailed flanges and an abutment shoulder on the outer end 10 of the handle, said shoulder having an edge opening socket therein, an apertured threaded disk set into the handle above the socket, a brush head having side edge dove-tailed flanges slidable in the backing flanges and 15 having an abutment shoulder at its inner end, and eye bolt projecting from the last named shoulder to be received in the backing socket when the two shoulders are in abutting engagement and a screw pin threaded through 20 the disk and passing through the eye bolt to retain the brush head on the backing.
2. A brush comprising a back, a handle on the backing, the backing being cut-away on one face to provide side dove tailed flanges 25 and an abutment shoulder on the outer end of the handle, said shoulder having an edge opening socket therein, an apertured threaded disk set into the handle above the socket, a brush head having side edge dove-tailed 30 flanges slidable in the backing flanges and having an abutment shoulder at its inner end, an eye bolt projecting from the last named shoulder to be received in the backing socket when the two shoulders are in abutting engagement 35 and a screw pin threaded through the disk and passing through the eye bolt to retain the brush head on the backing, and said brush head having a finger receiving depression therein at its inner end to facilitate 40 removal of the front head from the backing.

In testimony whereof I affix my signature.

SALVATORE MAZZELLA.
